UNITED STATES PATENT OFFICE

ANTON FAZEKAS, OF SAN FRANCISCO, CALIFORNIA

DESIGN FOR A MINIATURE-GOLF-COURSE HAZARD

Application filed November 5, 1930. Serial No. 37,554. Term of patent 7 years.

To all whom it may concern:

Be it known that I, ANTON FAZEKAS, a citizen of the United States, residing in the city and county of San Francisco, State of California, have invented a new, original, and ornamental Design for a Miniature-Golf-Course Hazard, of which the following is a specification, reference being had to the accompanying drawing, forming part thereof:

Fig. 1 is a side elevation of a miniature golf course hazard, or analogous article; and
Fig. 2 is a front elevation of the same.

I claim:

The ornamental design for a miniature golf course hazard, or analogous article, as shown.

ANTON FAZEKAS.
